HOT WATER HEATER

Stephen N. Bobo, New York, N. Y., assignor to
Robert P. Sniffen, New York, N. Y.

Application November 22, 1939, Serial No. 305,601

2 Claims. (Cl. 122—250)

My present invention relates to water heaters, and more particularly to an improved water heater of the instantaneous type.

In my improved heater I divide the heating coils into two sections or zones arranged one above the other, and pass the water to be heated through the coils in series and with the lowermost coil section subjected to direct heat from a burner, and with the uppermost coil section subjected to the action of indirectly applied heat. The uppermost coil section is arranged as the cold water receiving coil section, and therefore such water is preheated to a considerable degree before entering the lowermost coil section. The coil sections are arranged in frusto-conical form, and with the larger ends adjacent each other, thereby forming a cavity in which is arranged the actual burner. The burner is so constructed as to direct a radial heat downwardly upon the interior of the lowermost coil section and the burner is arranged with perforations which will permit the heat to rise upwardly.

The coil sections and burner are arranged within a suitable casing which may be cylindrical or rectangular. Extending inwardly from the inner surface of the casing are baffle plates which allow the heated gases to accumulate and move upwardly in the casing relative to the coil sections to a discharge orifice.

A feature of my invention therefore is an improved hot water heater of the instantaneous type.

A further feature of my invention is an improved instantaneous water heater in which the water containing coils are constructed in frusto-conical form and are assembled to define a central chamber in which is located the burner elements.

A still further feature of my invention is an improved instantaneous water heater in which the water is preheated prior to being brought into position to be heated by direct radiation from the heating element.

A still further feature of my invention is an instantaneous water heater in which the coils are arranged in sections and in which the water is fed into the uppermost section to be preheated and then downwardly into the lowermost coil to be heated to the required degree.

Other features of the invention and novel constructions of apparatus embodying the same will appear as the description of the invention progresses.

In the accompanying drawings

Fig. 1 is a vertical section, partly in elevation, through a heater embodying my invention.

Fig. 2 is a sectional view on the line 2—2 of Fig. 1, looking in the direction of the arrows, and

Fig. 3 is a perspective view of the ceramic element assembly of the burner shown in section in Fig. 1, and in plan view in Fig. 2.

Referring to the drawings, 10 designates a casing of any suitable form, but preferably cylindrical, provided with a bottom 11 and with a top 12. The casing 10 rests on a supporting frame 13, so constructed as to permit a free circulation of air beneath the casing 10. The top 12 is provided with a gas discharge orifice 14, through which the waste or spent gases of combustion may pass into the open air, or into a suitable chimney.

At the top of the casing 10 and extending through the material thereof is an inlet nipple 15, secured in position by the nut 16. This nipple 15, as is usual, is threaded as shown to facilitate connection to a source of water supply.

Within the interior of the casing 10 the nipple 15 is provided with two internally threaded portions 17 and 18 respectively, and the interior of such portions communicate with the interior of the nipple 15.

Secured or attached to the portion 17, by threading or sweat fitting, or the like, is a tubular member 19. This member 19 is formed integral with a coil 20 formed generally in the

form of a frustum of a cone, and which at its lower end is provided with a union 21. Secured

or attached to the portion 18 in any suitable manner is a tubular member 22 which is formed integral with a coil 23 formed generally in the

shape of the frustum of a cone and which, as shown in Fig. 1, encloses the coil 20. The lower

end of this coil 23 is located diametrically opposite the lower end of the coil 20 and has secured thereto a union 24.

The coils 20 and 23, are in general in the form

of a frustum of a cone, and one nested within

the other, and occupy a space substantially equal to one-half the height of the casing 10.

Adjacent the lower end of the casing 10 is a discharge nipple 25 which passes through the

wall of the casing 10 and is secured in position

by the nut 26. This nipple 25 has two portions

27 and 28 respectively, the interior of which

communicate with the interior of the outlet nipple

25. Secured to the portion 27 is a tubular mem-

ber 29 which is integral with and forms a part of

a coil 30, formed generally in the form of a

frustum of a cone, and which is located with its

larger end uppermost. At the end of the coil

30 is secured a threaded member 31 which co-

operates with the union 21 to make a water-tight

connection between the coil 30 and the union 21.

Other features of the invention and novel con-

structions of apparatus embodying the same will

appear as the description of the invention pro-

gresses.

In the accompanying drawings

Fig. 1 is a vertical section, partly in elevation, through a heater embodying my invention.

connection between the coil 23 and the coil 30 so that there is a water tight path from the inlet nipple 15 through the coils 23 and 20 and out through the discharge nipple 25.

5 Secured to the portion 28 is a tubular member 32 which is formed integral with and forms the part of a coil 33 formed generally in the frustro-conical form, and located within the coil 30 and with its larger end uppermost. The upper end 10 of the coil 33 has secured thereto an externally threaded member 34 which cooperates with the union 24 to form a water-tight connection between the coil 20 and the coil 33. Thus there is provided a water-tight path from the supply nipple 15 through the coils 20 and 33 and out through the discharge nipple 25. The upper end of the coils 30 and 33 are, as shown, spaced apart from the lower end of the coils 20 and 23 and, therefore, there is provided a relatively large space 15 between the two sets of coils in which may be housed the burner to be hereinafter described.

15 Mounted on the upper ends of the coils 30 and 33 adjacent to the externally threaded members 31 and 34 is an annular plate ring 35. The inner 20 diameter of the plate ring 35 is stepped, as indicated at 36, to provide a seat or shelf for a burner to be hereinafter described. Extending upwardly from the annular stepped plate 35, and preferably 25 symmetrically arranged about said plate, are standards 30 on posts 37. These posts are secured in position on the plate 35 by nuts 38. The posts 37 are so formed as to follow generally the outer 30 conical contour of the coil 23. Such posts also are threaded at their upper ends and pass through 35 perforations in a baffle plate 39, such baffle plate 39 being secured in position on the posts 37 by means of the nuts 40.

35 The baffle 39 is provided with perforations to permit escape of spent gases of combustion, and 40 also is provided with a centrally arranged perforation through which extends a threaded screw 41. To the lower end of the screw 41 is screwed a burner 42. This burner cooperates with a ceramic assembly designated generally by the 45 reference numeral 43 and which preferably and for convenience in manufacture and assembly is composed of a plurality of sectors 44.

45 The sectors 44 when assembled in the unit 43 define a central passageway 45 and a seat on the 50 lower face against which the upper end of the burner 42 seats and engages. Also the lower peripheral face of the sectors 44 seat in the step 36 formed in the annular stepped plate 35. Further, on the lower face of the sectors 44 are 55 arranged the closely packed downwardly extending points 46. The sectors 44 are composed of heat resisting non-combustible material of any suitable ceramic material and in operation the downwardly extending points become incandescent 60 and radiate heat generally downward over the entire area of the burner 43. The sectors 44 are also provided with perforations 47 extending through the same and preferably equal in number to the number of points 46. These 65 perforations 47 permit heated gases to pass upwardly through the burner elements and into engagement with the coils 20 and 23 in the upper half of the casing 10.

65 The lower bottom 11 of the casing 10 is centrally perforated to permit the attachment thereto of the lower end 48 of a gas tuyère 49. The upper end of the gas tuyère 49 is connected by means of screws 50 with the lower entrance end of the burner 42. The lower end 48 of the tuyère 70 is provided with a perforated diaphragm 51 on

which is rotatably mounted a perforated cover 52, and which may be rotated through any desired angle to control the flow of air into the casing connecting member 49. Gaseous fuel is fed to the tuyère 49, and thence to the burner 42 5 from a source of supply through the feed pipe 53 and nipple 54.

Within the casing 10 and surrounding the sets of coils above referred to are baffle plates 55, 56 etc. These baffle plates are secured at their outer 10 periphery to the inner surface of the casing 10, and their periphery is only slightly larger in diameter than that portion of the coils 23 and 30 with which such plates are adjacent. In this manner there is provided a series of baffles for 15 each of the coils 23 and 30 and which permit the heated air or gases to flow upwardly but always closely adjacent to the coils 23 and 30, which thereby are assured of being brought into contact with as great an amount of heated gas or products 20 of combustion as possible.

When constructed and assembled as above described and with the supply nipple 15 connected to the source of water supply and with the discharge nipple 25 connected to the suitable discharge fixtures water may be turned into the sets of coils. The water flows through the individual elements 20, 23 and 30, 33 of the sets of coils, in parallel. If gaseous fuel is turned into the burner 42 and ignited the flame from the gaseous fuel 30 will bring the points 46 of the burner elements 44 to incandescence and the heat generated will be directed downwardly into engagement with the coils 30 and 33. The water in such coils will be heated and upon proper manipulation of the 35 apparatus at the discharge fixtures water will flow downwardly through the set of coils 20 and 23 and downwardly through the set of coils 30 and 33 and out through the discharge nipple 25. The heat generated by the burner 42 will, after being directed downwardly as above described, naturally 40 rise and will, because of the discs 56 be held in close association with the coils 30 and 33. Also the heated gases will flow upwardly through the perforations 47 and the heated and practically 45 waste products of combustion will be brought into engagement with the set of coils 20 and 23. The water flowing through the sets of coils therefore will be heated in a direction opposite to the direction of flow, so that the water lying within the 50 coils 20 and 23 will be preheated before such water passes into the zone of direct heat by means of the burner 42 and ceramic assembly 43.

Whereas I have described my invention by reference to specific forms thereof, it will be understood that many changes and modifications may be made without departing from the spirit of the invention.

I claim:

1. In an improved hot water heater of the instantaneous type, the combination of a tubular heating element comprised of independent sections, each section of frustro-conical form, and arranged with the largest ends thereof adjacent to each other, said tubular sections arranged one above the other, and designed to have the water to be heated passing from the uppermost section to the lowermost section, the positioning of the sections defining a centrally arranged chamber, a burner within said chamber, and adapted to direct heat generated thereby directly downward onto the lowermost coil section, and means for directing the waste heat upwardly into engagement with the uppermost section.

2. In a hot water heater of the instantaneous

type, the combination of a casing, a tubular coil heater located within the casing and comprised essentially of two sections—an upper and a lower section—each section being of substantially frusto-conical form, and with the ends thereof of greater dimension arranged adjacent to each other to thus define a substantially centrally located chamber, a water inlet at the smaller end of the uppermost heating coil, a discharge outlet at the

lowermost end of the lowerly arranged coil, a burner located in said chamber, the said burner so arranged as to direct heat directly downwardly into association with the lowermost coil section, and means secured to the casing for directing heat upwardly into association with the uppermost coil section.

STEPHEN N. BOBO.
